UNITED STATES PATENT OFFICE.

GEORGE HOWLETT DAVIS, OF WEST ORANGE, NEW JERSEY.

EXPRESSION MECHANISM FOR SELF-PLAYING MUSICAL INSTRUMENTS.

No. 868,650.

Specification of Letters Patent.

Patented Oct. 22, 1907.

Application filed April 18, 1905. Serial No. 256,224.

To all whom it may concern:

Be it known that I, GEORGE HOWLETT DAVIS, a citizen of the United States, residing at West Orange, in the county of Essex and State of New Jersey, have invented new and useful Improvements in Expression Mechanism for Self-Playing Musical Instruments, of which the following is a specification.

My present invention relates to certain new and useful improvements in mechanically operated musical instruments, and more especially to an improved expression or phrasing mechanism for such instruments.

The prime object of the invention is to provide manually operable means under the control of the performer, for giving variations in expression to the musical composition, and to enable the bass, middle or treble keys of the piano to be independently controlled without causing a sudden or abrupt change in the musical tones.

It is a well-known fact that the musical tones in a piano may be modified or varied by altering or changing the position of rest of the hammers relatively to the strings, just prior to the stroke thereof, assuming of course, that the hammer actuating means always impels the hammers with the same degree of force. In other words, a hammer will strike a harder blow and cause a greater vibration of its string, when it travels its full distance or stroke, than when its stroke is shortened. Various means have heretofore been employed to move the hammer rest rail and thus change the position of rest of the hammers to modify the musical tones, but in all these prior devices, so far as I am aware, it is customary to locate such mechanism in the upper part of the piano associated with the hammer rest rail. Such arrangements are objectionable, especially in self-playing attachments where all the key-operating mechanism is located in the lower part of the piano case, because if either of the types of tone modifying mechanisms just above referred to were employed in connection with such attachments, the attachment would not be self-contained, so to speak, which is an all-important factor in mechanism of this class. In other words, it is very important that all the actuating and controlling mechanisms be located at about the same place in or on the piano.

A further purpose of the present invention is therefore, to provide means associated with the actuating elements, whereby the position of said elements relatively to the actuating means therefor, may be changed at the will of the performer to vary the extent of movement thereof and thereby of the sound producing devices.

In self-playing attachments of the type herein referred to, it has been the usual custom to cause the striker rods or key actuating elements, to act directly upon the keys of the musical instrument or upon a part

attached to each key. This is objectionable for the reason that when the attachment is in operation the keys are seen to move, which is not only entirely unnecessary but sometimes proves to be very annoying.

Another object of the present invention, therefore, is to provide means whereby the striker rods or actuating elements may be caused to impinge the rear end of the keys, or may be caused to act directly upon the piano action in which latter case the keys will remain at rest during the playing operation. I also provide means for shifting the operative ends of the striker rods or key-actuating elements, so that they may be caused to act either upon the keys or upon the action proper, said means being under the control of the performer.

To these ends the invention consists in the novel features of construction and combinations and arrangements of parts hereinafter referred to and more particularly defined in the claims following the specification.

In order to enable others to understand, make and use my said invention, I will now proceed to describe the same in detail, reference being had for this purpose to the accompanying drawings, in which—

Figure 1 is a sectional elevation illustrating my improved mechanism applied to a well-known type of playing attachment. Fig. 2 is a perspective view of the controlling mechanism for the key-actuating elements. Figs. 3, 4, 5, 6 and 7 are diagrammatic views illustrating the various positions assumed by the key-actuating elements in obtaining different musical effects. Fig. 8 is a side elevation of a complete train of mechanism from the actuating mechanism to the sound-producing device, which, in the present instance, is represented as a piano hammer.

I have shown my improvement as applied to a well-known type of self-playing attachment, although I wish it to be understood that I do not limit myself to the application of such improvements to the special type of mechanism herein shown, as such improvements may be applied to other types of self-playing attachments without departing from the spirit of the invention.

Referring to Fig. 1 of the drawing, the reference numeral 1 indicates a shaft journaled at its opposite ends in suitable hangers, one of which is indicated by the reference numeral 2, said hangers being attached to and depending from the rear underside of the keyboard of the piano, said shaft being rotated through the medium of a belt 3, or otherwise driven from any suitable motor. Supported between and secured to the hangers 2 is a magnet-supporting rail consisting of an L-shaped bar 4, on which is fixed a plurality of electromagnets 5, one for each key of the piano. Fixed to the said magnet bar is a plurality of springs 6, one for each magnet, each of which supports an armature 7 and a pendent rod 8, and to the lower ends of said rods are

pivoted as at 9, suitable actuating devices, such devices in the present instance comprising friction shoes 10, the arrangement being such that when the magnet's are demagnetized and the armatures in their raised positions, the lower curved ends 11 of the shoes will be held suspended out of engagement with the shaft 1, but in close proximity thereto.

The reference numeral 12 indicates one of the key-actuating elements in the present instance shown as a 10 striker rod, there being one of such elements or rods for each shoe and key. Each rod is pivoted at its lower end to the outer upper corner of its friction shoe and is vertically movable in rear of the key-board of the piano and arranged at its upper end to impinge the 15 under side of the pin 13 on the rear end of the piano key 14, and thus raise the latter to actuate the proper sound producing device and sound the corresponding note. It will be apparent from the foregoing that when any one of the magnets 5 is energized, its armature 7 20 will be attracted thereby forcing the corresponding shoe into contact with the shaft 1, which latter is constantly rotated by its motor in the direction of the arrow shown in Fig. 1. The rotation of the drum in the direction indicated, will throw the shoe 10 in the direction of the arrow thereon, thereby thrusting upward the striker rod 13 and depressing the forward end of the corresponding piano key 14, and through the coöperating sound producing device sounding the corresponding note. When the magnet is demagnetized, the 30 spring 6 raises the armature and lifts the shoe out of engagement with the shaft 1, whereupon the shoe will drop by gravity back against the adjustable and movable rest rail now to be described.

It will be evident that any movement of the friction 35 shoe in the direction of the arrow thereon, will tend to raise its striker rod and with it the rear end of the piano key 14 and the piano action supported thereon. It will also be apparent that the raising of the action will throw the piano hammer (as seen in Fig. 8) toward the 40 string. Hence, if the friction shoe is given such movement initially prior to being brought into contact with the continuously rotating shaft, the position of the hammer relatively to the string will be varied corresponding to the movement given to the shoe and as the 45 shoe is always impelled by the continuously rotating shaft with the same degree of force, it will be seen that the stroke of the hammer upon its string will depend upon the position of the hammer relatively to the string before the shoe is impelled.

50 The mechanism I employ for shifting the position of the shoe relatively to the continuously rotating shaft consists of a rest rail 15 arranged transversely with respect to the line of friction shoes, said rest-rail in the present instance being composed of two aligned sections 55 pivotally connected at their meeting ends by means of a pivot pin 16. These rest-rail sections are supported in such manner that they may be simultaneously or independently moved and may also be moved at an angle to each other and to a line taken centrally and longitudinally of the shaft, so that the position of all or only a group of the shoes relatively to the shaft may be changed or varied, whereby to vary the extent of movement of some of the shoes independently of the others, or to a greater degree than others, to produce various 60 gradations in the musical tones.

The outer ends of the rest-rail sections are secured to the depending arms 17 and 18, respectively; the upper end of the arm 17 being secured to a rock shaft 19 journaled in suitable bearings, as shown, and the upper end of the arm 18 being secured to a rock shaft 20 also journaled in suitable bearings. The adjacent hinged or pivoted ends of the rest-rail sections are secured to a depending arm 21, secured at its upper end to a rock shaft 22. These rock shafts are each provided with separate operating levers 23, 24 and 25, having suitable 70 finger-keys or buttons 26, all as shown and described in my pending application for Letters Patent, Serial No. 191,387.

By referring to Fig. 2 of the drawing, it will be seen that the finger keys 26 are marked with the characters 30 B, M and T, respectively; the key B controlling through the rock shaft 20, arm 18, and lever 23, one section of the rest rail and the bass keys of the piano; the key lettered M controlling through the rock shaft 22, arm 21, and the lever 24, the central or hinged portion of the rest rail, and the middle range of the piano; and the key lettered T controlling through the rock shaft 19, arm 17 and lever 25, the other section of the rest rail and the treble or upper part of the piano. It will be understood, therefore, that if the key lettered T is depressed, the right-hand section of the rest-rail will be thrust forward to move the friction shoes over the shaft and, at an angle to a line taken longitudinally and centrally of the shaft, in which 90 position one shoe will be slightly in advance of its adjacent shoe, as shown in Fig. 5 of the drawing. The same is true with respect to the key lettered B, only in this case the left-hand section of the rest-rail will be thus moved at an angle to the line taken centrally and longitudinally of the shaft, in which case 100 the shoes will assume a position corresponding to that shown diagrammatically in Fig. 4. If, on the other hand, both keys lettered B and T are depressed, both sections of the rest-rail will be thrust forward so that the shoes will assume the position illustrated in Fig. 105 6, and if only the central key lettered M is depressed, then the middle portion of the rest rail will be thrust forward in which case the shoes will assume the position indicated in Fig. 7. If all three keys are simultaneously depressed, then all the shoes will assume a 110 position corresponding to that illustrated in Fig. 3, in which case the line of shoes will lie parallel with a line taken centrally and longitudinally of the shaft, only the distance of travel of all the shoes will be shortened alike, and the notes sounded will all be the 115 same in character.

It will be apparent that the construction shown and described permits various other movements of the rest-rail and shoes, whereby to obtain different tone effects; and it will also be apparent that the extent 120 of movement of the shoes relatively to the shaft will depend entirely upon the extent of depression of the levers 23, 24 and 25.

From the foregoing it will be understood that the improvement sought to be protected resides broadly 125 in means for varying the position of the sound-producing devices or hammers relatively to the strings, said means coöperating with the actuating elements.

As mentioned in the brief statement of the objects of the present invention, a further feature resides in 130

so mounting the striker rods or other equivalent elements that they may be caused to act upon the rear end of the piano keys, or directly upon the action, and I will now proceed to describe the means whereby this end is reached.

The reference numeral 27, (see Fig. 1) designates a part of the piano action, of which the hammer (not shown) is another part. The lower end of the said part 27, rests upon a capstan screw 28, screwed into the rear end of each piano key, and it will be understood that whenever the rear end of the key is raised, the action will be operated. This is the case when, the striker-rod impinges the piano key or a part carried thereby, but in these constructions the front end 15 of the keys will be seen to be actuated when the attachment is operating, and this is objectionable, as before stated. To obviate this objection I attach to each part 27, or to any other suitable part of the action, an outstanding arm or bracket 29, having a head 20 at its lower end with which the upper end of the striker rod may engage when thrust upward by its shoe. With this construction it will be seen that the striker rods will act directly upon the action and in the playing operation the keys will remain at rest. 25 I also provide means for shifting the position of the striker rods so that they may be caused to act upon the keys, or directly upon the action as stated, said means consisting of an angle bar 31, extending lengthwise of the action, said bar being provided with a 30 plurality of apertures 32, through which the striker rods freely pass as shown. The angle bar 31 is moved backward and forward to accomplish the purpose above stated, by means of longitudinal arms 33, one attached to each end of the bar, said means sliding in slotted brackets 34, as shown. Stop pins or lugs 35 are carried by each arm 33 and arranged to engage the brackets 34, to limit the backward movement of the angle bar and insure proper positioning of the upper 40 ends of the striker rods relatively to the heads 30. The free ends of the arms 33 may project forward toward the front of the piano so as to be in easy reach of the performer.

I do not wish to be understood as limiting myself to the specific construction and arrangement of operating parts herein shown and described, as these may be varied to suit the particular type of instrument on which they are employed, it being understood that the showing herein is only by way of example.

In the appended claims I use the term "sound-producing device" to denote the piano hammer, the hammer action, or any similar device that is calculated to cause a vibration of a string or other sounder.

Having thus described my invention, what I claim as new and desire to secure by Letters Patent is:—

55 1. In expression mechanism for self-playing musical instruments, the combination with the sound-producing devices, of a plurality of actuating elements therefor, means for actuating said elements, and manually operable means under the control of the performer when in playing position at the instrument for shifting the position of said elements relatively to said actuating means whereby to increase or diminish the extent of movement of the said actuating elements and thereby of the sound-producing devices.

60 2. In expression mechanism for self-playing musical instruments, the combination with the sound-producing devices, of a plurality of friction shoes, means operable by

said shoes for actuating the sound-producing devices, a rotary shaft for operating the shoes, and manually operable means under the control of the performer when in playing 70 position at the instrument for shifting the position of the shoes relatively to the shaft whereby to increase or diminish the extent of movement thereof and thereby of the sound-producing devices.

3. In expression mechanism for self-playing musical instruments, the combination with the sound producing devices, of a plural 75 y of friction shoes, means operable by said shoes for actuating the sound-producing devices, a rotary shaft for operating the shoes, and manually operable means under the control of the performer when in playing 80 position at the instrument for shifting at will the position of the shoes relatively to the shaft whereby to increase or diminish the extent of movement thereof and thereby of the sound-producing devices.

4. In expression mechanism for musical instruments, 85 the combination with the sound-producing devices, of a plurality of friction shoes, striker rods operable by the 90 shoes for actuating the sound-producing devices, a rotary shaft for operating the shoes, and manually operable means under the control of the performer when in playing position at the instrument for shifting at will the position of the shoes relative to the shaft whereby to increase or diminish the extent of movement thereof and thereby of the sound-producing devices.

5. In expression mechanism for musical instruments, 95 the combination with the sound-producing devices, of a plurality of actuating elements therefor, means for actuating said elements, and manually operable means under the control of the performer when in playing position at the instrument for shifting the position of some of said 100 elements, independent of others, relatively to said actuating means, whereby to increase or diminish the extent of movement of the said actuating elements and thereby of the sound-producing devices.

6. In expression mechanism for musical instruments, 105 the combination with the sound-producing devices, of a plurality of actuating elements therefor, means for actuating said elements, and manually operable means under the control of the performer when in playing position at the instrument for shifting the position of some of said 110 elements, independent of others, relatively to the said actuating means, whereby to shorten the extent of movement of the actuating elements and thereby of the sound producing devices.

7. In expression mechanism for musical instruments, 115 the combination with the sound-producing devices, of a plurality of friction shoes for actuating said devices, a rotary shaft for actuating the shoes, a freely movable rest-rail for said shoes, and manually operable means under the control of the performer when in playing position at 120 the instrument for moving the rest-rail at will to change the position of the shoes relatively to the shaft.

8. In expression mechanism for musical instruments, 125 the combination with the sound-producing devices, of a plurality of friction shoes for actuating said devices, a rotary shaft for actuating the shoes, a freely movable rest-rail for said shoes, said rest-rail being made in sections and manually operable means under the control of the performer when in playing position at the instrument for moving the said rest-rail sections.

9. In expression mechanism for musical instruments, 130 the combination with the sound-producing devices, of a plurality of friction shoes for actuating said devices, a rotary shaft for actuating the shoes, a movable rest-rail for the shoes composed of separate independently movable sections, and means for independently operating either section of the rest-rail.

10. In expression mechanism for musical instruments, 135 the combination with the sound-producing devices, of a plurality of friction shoes for actuating said devices, a rotary drum for actuating the shoes, a movable rest-rail for said shoes, said rest rail being composed of flexibly connected sections, and manually operable means under the control of the performer for flexing the rest-rail intermediate its ends whereby to cause the middle range of shoes 140 to lie on converging lines.

11. In combination with the sound-producing devices

- and the manual keys for operating said devices, means for actuating said devices through the medium of the keys or independently thereof.
12. In combination with the sound-producing devices and the manual keys therefor, means for actuating said devices, and shiftable means for causing said actuating means to act directly upon the keys or upon the said devices.
13. In combination with the sound-producing devices, 10 and the manual keys therefor, an extension on each separate sound producing device, means for actuating said devices, and shiftable means for causing said actuating means to act upon the rear end of the manual keys or upon the said extensions.
14. In combination with the sound-producing devices and the manual keys therefor, an extension on each sound producing device, striker rods, and means for shifting said rods to cause them to engage the keys direct or the said extensions.
15. In combination with the sound-producing devices and the manual keys therefor, an extension on each sound producing device, striker rods, a bar having apertures through which the striker rods pass, and means for shifting the position of the bar to cause the striker rods 25 to act either upon the keys or upon the said extensions.
16. In combination with the sound-producing devices and the manual keys therefor, striker rods, a bar having apertures through which the striker rods pass, and means for shifting the position of said bar to cause the striker rods 30 to act either upon the keys or upon the said sound producing devices direct.
17. In combination with the sound producing devices of a piano, a playing attachment comprising a rotary shaft and a plurality of friction shoes coöperating therewith 35 for actuating said devices, a rest-rail coöperating with said shoes, and manually operable levers under the control of the performer for shifting at will the position of said rest-rail and shoes relatively to the shaft whereby to increase or decrease the extent of movement thereof and 40 thereby of the sound producing devices.
18. A piano having a playing attachment comprising a rotary shaft and a plurality of friction shoes, means actuated by the shoes for operating the piano hammers, and manually operable means under the control of the 45 performer when in playing position at the piano for shifting the position of said shoes relatively to the shaft whereby to increase or diminish the extent of movement
- thereof and thereby of the piano hammers relatively to the piano strings.
19. A piano having a playing attachment comprising a rotary shaft and a plurality of friction shoes, means actuated by the shoes for operating the piano hammers, a rest-rail for the shoes, a movable support for said rest-rail, and manually operable means under the control of the performer for actuating said movable support for the 55 purpose specified.
20. A piano having a playing attachment comprising a rotary shaft and a plurality of friction shoes, means actuated by the shoes for operating the piano hammers, a sectional rest-rail for the shoes, a movable support for said 60 rest-rail, and manually operable means under the control of the performer for actuating either section of the rest-rail independent of the other for the purpose specified.
21. In mechanism of the class described, the combination with the piano hammers, of a plurality of friction 65 shoes for impelling the hammers against their strings, means for actuating the friction shoes, and means for flexing the line of friction shoes intermediate the ends of the line for the purpose specified.
22. In mechanism of the class described, the combination with the piano hammers, of a plurality of friction 70 shoes arranged in a right line for impelling the hammers against their strings, means for actuating the friction shoes, and means for cutting a portion of the said line of shoes relatively to the actuating means and without 75 affecting the position of the remainder of the line, for the purpose specified.
23. A piano having a playing attachment comprising a rotary shaft and a plurality of friction shoes, means actuated by the shoes for impelling the piano hammers 80 against their strings, means coöperating with the friction shoes for shifting their normal position of rest relatively to the said shaft and thereby the position of the piano hammers relatively to their strings, and manually operable means under the control of the performer when in playing 85 position at the piano for operating said shoe-shifting means at will.

In testimony whereof I have hereunto set my hand in presence of two subscribing witnesses.

GEORGE HOWLETT DAVIS.
